DEVICE FOR REMOVING SEALS FROM
WATER WELLS AND OTHER PURPOSES

John B. Murphy, Freeport, N. Y., assignor to
American Water Works Company, Incorporated,
New York, N. Y., a corporation of Delaware

Application December 2, 1947, Serial No. 789,317

5 Claims. (Cl. 166—1)

1

The present invention relates to apparatus for removing liquid seals and the like from a cased well, and more particularly to new and improved apparatus of this character which is readily adapted to other purposes in wells.

Water wells, for example, are usually lined with metal casing which extends from the surface of the earth to the level of a water bearing formation. Generally several telescoping sections of casing of different diameters are used, the uppermost casing section having the greatest diameter. In so-called telescope pattern wells of this type, water seals are frequently used at points of reduction in casing size to prevent the intrusion of salt water or other foreign matter.

One type of seal comprises a metal reducing sleeve having a lower portion of reduced diameter which extends into a lower casing section of reduced diameter. A rubber collar is interposed between the reduced portion of the sleeve and the top of the lower casing section and the sleeve is held in position by a wooden ring driven into the space between the upper end of the sleeve and the adjacent upper casing section of greater diameter.

Heretofore, if either the casing or the seal failed, it was practically impossible to make necessary repairs because the seals, after use for a considerable period, could not effectively be removed.

It is an object of the invention, accordingly, to provide novel apparatus for removing liquid seals and the like from a well.

Another object is to provide new and improved apparatus of the above character which can easily enter a liquid seal and can be adjusted to apply a lifting force to the seal.

A further object of the invention is to provide new and improved apparatus of the above character having means preventing it from passing completely through a well seal, whereby a downward blow may be applied to said seal.

Still another object of the invention is to provide new and improved apparatus of the above character that can be operated from the surface of the earth.

A still further object of the invention is to provide novel seal pulling apparatus that can be readily adapted to other purposes in a well such as chasing threads in a casing or cutting a casing, for example.

In accordance with the invention, seal pulling apparatus is provided which comprises a support adapted to be lowered into a bore hole and

2

of such size that it can freely enter a liquid seal. The support carries a plurality of laterally movable arms that are normally maintained a minimum distance apart but can be extended outwardly a sufficient distance to prevent the apparatus from being withdrawn from the seal. The support also preferably carries a plurality of radially extending fins of such size as to prevent their passage through the lower, reduced diameter portion of a liquid seal.

Preferably, the fins and the movable arms are longitudinally spaced apart on the support a sufficient distance so that upward and downward blows, respectively, will be applied to the seal when the apparatus is reciprocated in the well. Means are also provided whereby extension and withdrawal of the lateral arms can be controlled from the surface of the earth.

By relatively simple modification, the seal pulling apparatus can also be readily adapted for other purposes in a well such as cutting or threading casing, for example.

The invention may be better understood from the following detailed description of several representative embodiments taken in conjunction with the accompanying drawings, in which:

Fig. 1 is a view in longitudinal section of a seal pulling device constructed according to the invention, shown in operative position in a water well, for example;

Fig. 2 is an enlarged view in longitudinal section of the portion of the water well between the lines A and B in Fig. 1;

Figs. 2A and 2B are views in transverse section taken along lines 2A—2A and 2B—2B of Fig. 2, looking in the direction of the arrows;

Fig. 3 is a view in transverse section showing apparatus constructed according to the invention for cutting the casing in a water well, for example; and

Fig. 4 is a view in transverse section showing apparatus according to the invention for cutting threads in a casing coupling or in a string of casing.

Referring now to Fig. 1, a bore hole 10 is shown drilled into the earth and lined with a string of casing comprising, for example, an upper section 11 of relatively large diameter, an intermediate section 12 of smaller diameter and a bottom section 13 of smaller diameter formed with perforations 14 at the level of a water bearing formation 15, for example. While three casing sections 11, 12 and 13 are shown in Fig. 1, wells of this type may have either a

greater or lesser number of casing sections of different diameter, as needed.

In order to prevent the intrusion of salt water or other foreign material, for example, into the well, it is customary to seal off the casing at the points where the casing is reduced from one diameter to a smaller diameter.

One form of seal that is commonly used comprises a reducing sleeve 16 having a lower necked portion 17 of reduced diameter which is adapted to extend within the upper end of the lower casing section 12, as shown in greater detail in Fig. 2. A collar 18, of rubber or other suitable material, is interposed between the reducing sleeve 16 and the upper end of the casing section 12 and is held tightly in place by means of a packer 19, usually made of wood, which is driven into the space between the upper end of the reducing sleeve 16 and the adjacent interior wall of the casing section 11 of larger diameter.

After seals of this type have been in place for a period of years, it has been found almost impossible to remove them to repair a leak or to renew a section of casing.

According to the invention, a novel seal pulling device is provided which is capable of removing a seal of this type effectively and in a relatively short period of time. As shown in Fig. 2, the seal pulling device 20 may comprise, for example, a substantially cylindrical casing 21 which may be lowered into the well 10 in any convenient manner, as, for example, on a string of pipe 22 supported at the surface of the earth by a conventional type cable drilling rig 23 (Fig. 1). The diameter of the casing 21 is made smaller than the diameter of the necked portion 17 of the reducing sleeve 16, but a number of fins 24 of greater diameter than the necked portion 17 are mounted on the upper portion of the casing 21. With this construction, the lower portion of the casing 21 can be lowered through the necked portion 17 but the entire device 20 cannot pass through because of the fins 24.

In the lower portion of the casing 21 are formed a plurality of longitudinally extending slots 25 (Fig. 2B) within which a plurality of arms 26 are pivotally mounted at 27 for lateral movement. The arms 26 are provided with lugs 28 at the upper ends thereof, which prevent them from falling out of the slots 25, and also carry downwardly and inwardly extending members 26a.

Each of the arms 26 is provided with an inner surface 29 which is adapted to cooperate with a disk-like member 30 secured on a rod 31 to extend or withdraw the arms 26 in the slots 25, as desired. To this end, the rod 31 is connected by a string of pipe 32, for example, within the string of pipe 22 to the drilling rig 23 at the surface of the earth by means of which it may be raised or lowered, as desired. When the rod 31 is lowered, its bottom end 31a engages the members 26a on the arms 26, thereby moving the latter to the retracted position. When the rod 31 is raised, the disk-like member 30 thereon moves the arms 26 outwardly to the extended position shown in full lines in Fig. 2.

The rod 31 is preferably provided with any suitable type of latch 33 which, when turned by the pipe 32, is adapted to cooperate with a ledge 34 formed within the casing 21 for the purpose of latching the disk-like member 30 in its uppermost position, as shown in Fig. 2.

In operation, removal of a seal of the general type described above is accomplished according

to the invention by first removing the plug 19. This may be done in any known manner as, for example, by cutting it out with a tubular saw-tooth cutter of conventional type commonly used for this purpose. The seal pulling apparatus is then lowered within the casing 11 with the rod 31 in its lowermost position so that the disk-like member 30 is at the lower end of the cam-like surface 29, and the arms 26 are retained within the casing 21, as shown in dotted lines in Fig. 2.

The lowering of the apparatus is continued until the lower portion of the casing 21 has passed through the necked portion 17 of the reducing sleeve 16 and the fins 24 rest upon the necked portion 17, as shown in Fig. 2. The rod 31 is then raised by pulling upon the string of pipe 32 at the surface of the earth. This moves the arms 26 outwardly to the position shown in full lines in Fig. 2. In this position, the arms 26 underlie the lower edge of the necked portion 17 and prevent the apparatus from being withdrawn through the reducing sleeve 16. The rod 31 is then latched in this position by rotating the string of pipe 32 at the surface of the earth until the latch 33 lies over the ledge 34.

The slack is then taken up on the supporting cable in the drilling rig 23 until the upper edges of the arms 26 engage the lower edge of the necked portion 17 of the reducing sleeve 16. The slack is further taken up until the compression spring of the walking beam 35 is fully compressed at the upper end of its stroke. For a compression spring rated at 6 tons at full compression, for example, the force of the spring, plus the inertia of the moving seal pulling apparatus 20 and the supporting string of pipe 22 causes a substantial blow to be struck on the reducing sleeve 16 at the lower edge of its necked portion 17.

By letting slack out on the supporting cable in the drilling rig 23, the guiding fins 24 on the casing 21 strike a downward blow on the reducing sleeve 16 that has the total weight of the seal pulling apparatus and the string of casing 22 behind it. By reciprocating the apparatus 20 in the well in the manner described above for a sufficient period of time, the reducing sleeve 16 is eventually free and can be removed intact from the well.

It will be understood that the fins 24 and the arms 26 should be properly designed both as to size, shape and materials so as to be able to withstand without damage the pounding applied to a seal.

In Fig. 3 of the drawings, an apparatus is shown which enables the well casing to be cut preparatory to the removal of a section from the well, for example. In this embodiment, the apparatus may be substantially the same as in Fig. 2 except that the arms 26' are provided with cutting wheels 36 which are rotably mounted on longitudinal axes in slots 37. The arms 26' may be connected by means of links 38 to a carriage member 39 threadedly mounted on lead screw 40 formed at the bottom end of the rod 31. The lower end of the rod 31 may be unthreaded and may extend through a transverse member 41 secured to the casing 21. The rod 31 may be secured to the transverse member 41 in any suitable manner as, for example, by means of the lock nuts 42, as shown.

In the form of the apparatus shown in Fig. 3, the apparatus is lowered within a well casing to the desired level and the string of pipe 32 is ro-

tated in the proper direction to cause the arms 26 to move outwardly until the cutting wheels 36 are in engagement with the casing. When this position is reached, the casing may be cut by rotating the cylindrical casing 21 by means of the string of pipe 22, for example.

The form of the invention shown in Fig. 4 enables threads to be cut within a casing or within a coupling. Here again, the apparatus is essentially the same as that shown in Fig. 2 except that the outer edges of the arms 26 are provided with thread cutting die portions 43. In operation, the apparatus is lowered into a well with the disk-like member 30 in its lowermost position so that the thread cutting die portions 43 of the arms 26 are out of engagement with the casing. When the apparatus is at the proper level in the well, the disk-like member 30 is raised by the rod 31 until the thread cutting die portions 43 are in engagement with the casing. The thread is then cut by rotating the cylindrical casing 21 of the apparatus by means of the string of pipe 22, for example, until a thread of desired depth has been cut.

Obviously, the fins 24 need not be employed with the forms of the invention shown in Figs. 3 and 4. Further, the latching device 33, 34 of Fig. 2 is not necessary in the apparatus of Fig. 3.

From the foregoing, it will be apparent that the invention provides a novel and highly effective device for pulling seals in wells drilled in the earth. By virtue of the construction described and illustrated herein, the seal pulling apparatus may be readily lowered partially through the seal and the arms extended so as to enable heavy blows to be applied above and below the necked portion of the seal. The apparatus is further susceptible of easy modification for other uses in a well, such as, for example, cutting casing or threading casing, as desired.

Obviously, the several specific embodiments described above can be modified within the spirit of the invention. The general sizes and shapes of the parts may be varied as necessary to suit conditions in a particular well and any suitable materials may be used. Instead of supporting the apparatus on the string of pipe, as shown in Fig. 1, obviously it might be carried by a cable of sufficient strength for this purpose. The several forms disclosed herein have been given merely by way of illustration and are susceptible of numerous changes in form and detail within the scope of the appended claims.

I claim:

1. In apparatus for use in a well or the like, the combination of a body adapted to be lowered into a well, said body having a lower portion that can pass through an opening of given diameter and an upper portion that is incapable of passing through said opening, a plurality of radially extensible and retractable arms pivotally mounted at said body lower portion, each of said arms extending upwardly from its pivot to a flat striking surface disposed substantially perpendicularly to the longitudinal axis of the well and having a member extending inwardly and downwardly from said pivot, an actuator member having portions engaging the inner edges of said arms for moving said arms to extended positions when the actuator member is raised relatively to the body, and having another portion adapted to engage said inwardly extending members when the actuator member is lowered relatively to the body to move them outwardly, thereby moving said arms to retracted positions with respect to the

body when the actuator member is lowered relatively to the body, means for operating said actuator member from the entrance to the well, releasable latching means for securing said actuator member to the body in the position to maintain said arms extended, and means for lifting said body in the well to cause said arms to deliver a blow to an element in the well.

2. In apparatus for use in a well or the like, the combination of a body adapted to be lowered into a well, a plurality of radially extensible and retractable arms pivotally mounted on said body, each of said arms extending upwardly from its pivot to an upper blow delivering edge disposed substantially perpendicularly to the longitudinal axis of the body and having a member extending downwardly and inwardly from said pivot, lug means formed at the upper ends of each of said arms and adapted to cooperate with said body to limit radial extension of said arms; an actuator member in the body, said actuator member having radially extending portions adapted when raised to engage the inner edges of said arms to move said arms to extended position, and having a downwardly extending portion adapted when lowered to engage the downwardly and inwardly extending members on the arms to move said arms to retracted position, means operable from the surface of the earth for raising and lowering said actuator member, and releasable latching means for securing said actuator member to the body in the position to maintain said arms extended.

3. In apparatus for removing a casing element in a well or the like, the combination of a body adapted to be lowered into a well, a plurality of radial fin members secured on the body, each of said fin members having a lower blow-delivering edge disposed substantially perpendicularly to the longitudinal axis of the body, said fin members projecting radially a sufficient distance to prevent passage thereof through said casing element, a plurality of radially extensible and retractable arms pivotally mounted on the body below said fin members and spaced apart therefrom, each of said arms extending upwardly from its pivot to an upper blow delivering edge disposed substantially perpendicularly to the longitudinal axis of the body and having a member extending downwardly and inwardly from said pivot, lug means formed at the upper ends of each of said arms and adapted to cooperate with said body to limit radial extension of said arms, an actuator member in the body, said actuator member having radially extending portions adapted when raised to engage the inner edges of said arms to move said arms to extended position, and having a downwardly extending portion adapted when lowered to engage the downwardly and inwardly extending members on the arms to move said arms to retracted position, means operable from the surface of the earth for raising and lowering said actuator member, said arms in retracted position being capable of passage through said casing element but being incapable of passage through the casing element when extended, releasable latching means for securing said actuator member to the body in the position to maintain said arms extended, and means at the entrance to the well for moving said body upwardly to cause said arms to deliver a blow to said element in the well, and for moving said body downwardly to cause said fin members to deliver a blow to said element in the well.

4. In apparatus for use in a well or the like, the combination of a body adapted to be lowered into a well on a string of pipe or the like, said body having a plurality of longitudinally extending slots therein angularly spaced about the longitudinal axis thereof, a plurality of arms pivotally mounted on the body for lateral movement in said slots, each of said arms being formed so as to diverge upwardly from its pivot point to a flat, upper blow-delivering edge disposed substantially perpendicularly to the axis of the body, lug means on the upper ends of each of said arms and disposed within said body so as to form stop means limiting transverse movement of said arms, downwardly and inwardly extending retractor means formed on each of said arms, and arm actuator means suspended in said well on a support extending to the surface of the earth, said arm actuator means comprising a disc-like portion adapted, when raised with respect to the body, to cooperate with the inner edges of said arms to extend them laterally from the body, and a rod-like portion adapted, when lowered with respect to the body, to engage said retractor means on the arms to retract them from their extended position.

5. In apparatus for removing a casing element in a well or the like, the combination of a body adapted to be lowered into a well on a string of pipe or the like, a plurality of longitudinally extending fins secured to the body and angularly spaced about the longitudinal axis thereof, said fins projecting radially a sufficient distance to prevent passage thereof through said casing element, means forming a plurality of longitudinally extending slots in the body below said fins, said slots being angularly spaced about the longitudinal axis of the body, a plurality of arms pivotally mounted on the body for lateral movement in said slots, each of said arms being formed so as to diverge upwardly from its pivot point to a flat, upper blow-delivering edge disposed substantially perpendicularly to the axis of the body, lug means on the upper ends of each of said arms and disposed within said body so as to form stop means limiting transverse movement of said

5
